VALVE CLOSURE FOR COLLAPSIBLE TUBES

Edward J. Richards, Philadelphia, Pa.

Application April 29, 1932. Serial No. 608,294

9 Claims. (Cl. 221—60)

The object of the invention is to provide an improved valve or cap, adapted to be used as a closure for collapsible tubes, and for other devices from or through which fluid, semi-fluid and plastic substances flow intermittently.

Another and more specific object is to provide a valve of this type, which effectually severs the extruded substance from that still remaining within the tube or other container, which is preferably permanently mounted upon the discharge head of the tube, and which is also preferably yieldingly maintained in closed position, wherein it is easy with the usual toothbrush or the like to remove all trace of the extruded substance from the said tube head, it being understood that the invention can be applied to containers and dispensing devices of various sorts, and in each instance provides an exceedingly simple, efficient and wholly sanitary article.

With these and other objects in mind, the present invention comprises further details of construction and operation, which are fully brought out in the following description when read in conjunction with the accompanying drawing, in which Fig. 1 is a fragmentary portion of a well-known shape of toothpaste tube equipped with one embodiment of the invention; Fig. 2 is a vertical, diametrical section of the tube and closure of Fig. 1, but shown in separated spaced relation; and Fig. 3 is a top plan view of the tube per se, the closure not having been attached thereto.

Referring to the drawing, any well-known type of tube, such as is used for toothpaste and similar substances, is shown as comprising a tubular body portion 1, which merges into a frustoconical end portion 2, which in turn opens into a hollow cylindrical head 3, having a closed end portion 4, and through one side wall of which head opens a discharge aperture 5. Said end portion of this head is provided with an elongated recess 6, extending radially thereinto from one side thereof, said recess housing any suitable form of resilient member 7, such as a coil spring or the like, and a locking member 8, which is maintained in an extended position by means of said spring. The closure for the head of this tube comprises an imperforate cylindrical member 9, the lower free edge 10 of which is acutely angular in cross-section and is adapted to slide along and in close proximity to the outer surface of the head 3, so as to sever material extruded from within said tube through the aperture 5 and thereby separate this portion of such substance from that remaining within the tube.

The inner cylindrical surface of said closure is provided with a longitudinally extending groove 12, which terminates at 13 in spaced relation with the severing edge 10, and is deeper at its inner end portion 14 than throughout the remainder of its length.

In order to assemble this closure upon the head above described, the locking member 8 is pressed into the recess 6 of the latter and the closure slipped over said head. Upon releasing said locking member and moving said closure until said member is in alignment with the groove 12, said member is pressed outwardly by the spring 7 into said groove, thereby preventing the subsequent separation of said closure from said head. Also, it will be noted that, by reason of the increased depth of the innermost portion 14 of said groove, as the locking member 8 enters this deeper portion, it tends to yieldingly resist outward movement of said closure upon and with respect to said head, though yielding under the relatively light pressure of said spring to permit the withdrawal of said closure and exposure of the discharge aperture 5, when and as may be desired.

Although but one embodiment of the invention is here illustrated and described, it is to be understood that the invention comprises various constructions in which a locking member resiliently carried by the discharge head of a tube or other container extends yieldingly into an internal groove or recess within a closure, which is telescopically carried by said head, and which upon being moved in one direction, severs from said head that portion of the substance from within the tube which has been extruded through the discharge aperture.

Having thus described my invention, what I claim and desire to protect by Letters Patent of the United States is:—

1. The combination of a receptacle having a head through one side wall of which a discharge aperture extends and provided with a recess, a hollow imperforate closure having a beveled cutting edge slidably upon said head and operative when moved into closed position to sever extruded from unextruded substance within said receptacle, said closure having a longitudinal groove normally registering with said recess and retaining means extending within and between and yieldingly engaging the inner surface of said closure to secure the closure upon said head.

2. The combination of a receptacle having a head through one side wall of which a discharge aperture extends, a hollow imperforate closure

- having a beveled cutting edge slidable upon said head and operative when moved into closed position to sever extruded from unextruded substance within said receptacle, said closure having an internal recess in a side wall of greater depth at its innermost portion, and retaining means yieldingly engaging within said recess to secure the same upon said head, and when engaging the deeper portion of said recess yieldingly maintaining said closure in operative closed position. 6. The combination of the telescoping discharge head of a receptacle and an imperforate closure mounted thereon and normally covering a laterally opening discharge aperture in said head, a radially movable member carried by said head and engaging within an internal groove in and terminating short of the free edge of said closure, and a spring to maintain said member in extended position, to prevent the rotation and removal of said closure from said head. 80
3. The combination of a receptacle having a head through one side wall of which a discharge aperture extends, a hollow imperforate closure having a beveled cutting edge slidable upon said head and operative when moved into closed position to sever extruded from unextruded substance within said receptacle, said closure being provided with a longitudinal groove, a reciprocatory member carried by said head and engageable within said groove, and resilient means to normally maintain said member in extended operative position. 7. The combination of a receptacle having a head provided with a discharge aperture, a radially movable locking member carried by said head, resilient means to maintain said member in extended position, and a closure slidable upon said head to cover said head when in one position and provided with a groove having a portion of greater depth at one end, said locking member extending into said groove and adapted to enter said deeper portion to yieldingly maintain said closure in a given predetermined position. 85
4. The combination of a receptacle having a head provided with a laterally directed discharge aperture, a closure slidably mounted upon said head and having an internal longitudinally extending groove, the edge of said closure wiping closely across said aperture, said head being provided with a radially extending recess opening in one direction, a locking member slidable within said recess and its free end portion extending into said groove, and resilient means also within said recess to maintain said member in operative extended position. 8. The combination of a receptacle having a head provided with a discharge aperture in one side wall, a radially movable locking member carried by said head and normally extending laterally therefrom, resilient means to maintain said member in extended position, and a closure longitudinally slidable upon said head to cover said head when in one position and provided with a groove having a portion of greater depth at its inner end, said locking member extending into said groove and adapted to enter said deeper portion to yieldingly maintain said closure in operative position closing said aperture. 100
5. The combination of a receptacle having a cylindrical head provided with a laterally directed discharge aperture, a closure slidably mounted upon said head and its free edge wiping along the surface of said head across and in close relation to said aperture, said closure being provided with an internal groove which stops short of the free edge of the closure and is deeper towards its innermost portion, said head being provided with a radially extending recess opening in one direction, a locking member slidable within said recess and its free end portion extending into said groove, and resilient means also within said recess to maintain said member in operative extended position, to prevent separation of said closure from said head and tending to maintain said closure in operative closed position. 9. The combination of a receptacle having a head through one side wall of which a discharge aperture extends, a hollow imperforate closure having a beveled cutting edge slidable upon said head and operative when moved into closed position to sever extruded from unextruded substance within said receptacle, said closure being provided with a longitudinal groove, of greater depth adjacent to one end, a reciprocatory member carried by said head and engageable within said groove, and resilient means to normally maintain said member in extended operative position, preventing removal of said closure from said head, and said member when engaging the deeper portion of said groove being operative to yieldingly retain said closure in one extreme position. 110 115 120 125
